DESIGN FOR A GOBLET OR SIMILAR ARTICLE

Rowena Reed Kostellow, Pittsburgh, Pa., assignor to United States Glass Co., Pittsburgh, Pa., a corporation of Pennsylvania

Application January 22, 1938, Serial No. 74,489

Term of patent 3½ years

To all whom it may concern:

Be it known that I, Rowena Reed Kostellow, a citizen of the United States, residing at Pittsburgh, Allegheny County, State of Pennsylvania, have invented a new, original, and ornamental Design for a Goblet or Similar Article, of which the following is a specification, reference being had to the accompanying drawing, forming part thereof, in which:

Fig. 1 is an elevation of a goblet showing my design;

Fig. 2 is an elevation taken at right angles to Fig. 1; and,

Fig. 3 is a horizontal section on the line 3—3 of Fig. 1.

The dominant feature of the design is the surface ornamentation and wall ornamentation of the article as shown in full lines in the drawing.

What I claim is:

The ornamental design for a goblet or similar article, substantially as shown and described.

ROWENA REED KOSTELLOW.
